(57) **CLAIM**

The ornamental design for an electrical plug adapter, as shown and described.

DESCRIPTION

FIG. 1 is a front, bottom, right perspective view of an electrical plug adapter showing our new design;

FIG. 2 is a back, top, right perspective view thereof;

FIG. 3 is a front elevational view thereof;

FIG. 4 is a back elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is an exploded back, top, right perspective view thereof, shown with an insertable plug;

FIG. 10 is an exploded front, top, left perspective view thereof, shown with an insertable plug;

FIG. 11 is a back, top, right perspective view thereof, shown with an insertable plug in an inserted state;

FIG. 12 is a front, top, left perspective view thereof, shown with an insertable plug in an inserted state;

FIG. 13 is an exploded back, top, right perspective view thereof, shown with an insertable plug and an insertable extension cord;

FIG. 14 is an exploded front, top, right perspective view thereof, shown with an insertable plug and an insertable extension cord;

FIG. 15 is a back, top, right perspective view thereof, shown with an insertable plug and an insertable extension cord, both in an inserted state; and,

FIG. 16 is a front, top, left perspective view thereof, shown with an insertable plug and an insertable extension cord, both in an inserted state.

The broken lines showing the insertable plug in FIGS. 9–16 and the insertable extension cord in FIGS. 13–16 depict environmental subject matter that form no part of the claimed design. All other broken lines depict portions of the electrical plug adapter that form no part of the claimed design.

1 Claim, 13 Drawing Sheets
